UNITED STATES PATENT OFFICE.

RICHARD FITZGERALD, OF CHICAGO, ILLINOIS.

FLUID-PRESSURE BRAKE.

No. 993,161.

Specification of Letters Patent.

Patented Oct. 16, 1906.

Application filed July 7, 1903. Serial No. 164,530.

To all whom it may concern:

Be it known that I, RICHARD FITZGERALD, of Chicago, Cook county, State of Illinois, have invented certain new and useful Improvements in Fluid-Pressure Brakes, of which the following is a specification.

My invention relates to what is commonly known and designated as a "triple valve" of a fluid-pressure brake system, and is intended as an improvement upon the particular type of valve device described and claimed in my prior patent, No. 608,661, issued August 9, 1898, and also described and claimed in Hibbard Patent No. 644,356, issued to me on February 28, 1900.

The object of my present invention is to improve the working of the valve device, and more particularly to provide means for preventing what is known in railroad parlance as "stuck brakes," which occasion great annoyance and losses to railroad companies in the way of flat wheels caused by the failure of the brake of a car to be released or pumped off.

In the drawings, Figure 1 is a central section of my valve device; and Fig. 2 a section on the line 2-2 of Fig. 1, taken through the service and emergency valve.

As herein shown the valve-casing is provided with a cap or cover 2 and two chambers 3 and 4, in the latter one of which is arranged the piston 13 and in the former one of which the diaphragm mechanism hereinafter more particularly described is substituted for the specific form of movable abutment or piston illustrated in Patent No. 644,356.

The valve-casing has the usual connection with the members of the brake system—as, for instance, with the train-pipe through the nozzle 6, (also denoted by T.P.) with the auxiliary reservoir at 8, (denoted by A.R.) and with the brake-cylinder 7, (denoted by B.C.)

The piston 13 travels in the chamber 4 and governs the by-pass 4^a, which permits the train-pipe air to feed from the chamber 4 to the auxiliary reservoir through the passages 26 and 26^a and past a certain valve, designated a "reservoir-feed controller," hereinafter explained.

The piston 13, as in said prior patent, No. 644,356, has a stem 16, which works within the emergency-valve 18. This latter valve, which remains seated, except in the emergency applications of brakes, governs the passage 23, which admits train-pipe air to the

brake-cylinder direct from the train-pipe and past the check-valve 24.

The stem 16 has a central end bore in which is arranged to reciprocate a pin 16^a, normally held projected by a coiled spring 16^b, located in the bottom of the bore. This pin constitutes, in fact, the service-valve, as it seats upon and controls the port 17 in the emergency-valve, through which port the auxiliary-reservoir air passes to the brake-cylinder. The stem 16 has two closed slots, 16^c, entering the bore thereof and receiving a pin 16^d, which passes through the service-valve and slides in the slots as the valve moves in and out of the stem 16. The object of this arrangement is to limit the outward movement of the service-valve, but permit of a slight inward movement, with the result that full pressure against the piston 13 will not cause the service-valve to seat with any great or unnecessary pressure upon its seat. To effect this result, the piston-chamber 4 is provided with a stop arranged to limit the movement of the piston 13 to the right, Fig. 1, and in the present instance this stop arrangement comprises a ring-like projection 13^a, forming part of the casting of the body of the valve device or casing.

As shown in Fig. 2, the forward portion of the stem 16 is provided with one or more longitudinal channels 14 for the passage of auxiliary-reservoir air. The emergency-valve is provided, as in said Patent No. 644,356, with a circumferential groove 18^a.

In the present instance I have shown the brake-cylinder release mechanism operated by a diaphragm instead of its mechanical equivalent, a piston, as shown in said prior patents hereinbefore referred to. As this diaphragm is illustrated in the drawings, I will describe it in a general way as follows: Between a top cap 50 and the upper end of the valve-casing is arranged or secured a ring 51, providing a diaphragm-chamber 3, having free communication with the atmosphere through its side in any suitable manner. This ring is provided with communication with the brake-cylinder through the passages 12 and 54, as indicated in dotted lines in Fig. 1. The spider-arm also has a passage 55, communicating with said passage 54, but closed as to its outer end by a plug 56, which arrangement is useful in case a pressure-regulating valve is employed—such as shown, for instance, in Patent No. 110

699,386, issued to me on May 6, 1902. The passages 54 and 55 communicate with the release-port, whose communication with the diaphragm-chamber 3 is controlled by the 5 release-valve 58, which, as herein shown, has a stem 58^a, preferably angular to permit the air to pass by. Diaphragms 61 and 62 are anchored or clamped at their margins in such manner as to be positioned in opposite ends 10 or sides of the diaphragm-chamber. Between these diaphragms is arranged a distance-block 63, movable with the diaphragms and arranged to contact the projecting stem of the release-valve, and thereby 15 hold such valve open in the normal condition of the brakes. When, however, in the application of the brakes the train-pipe pressure is reduced in the usual manner, the influence of the distance-block and the dia- 20 phragms is removed from the release-valve, whereupon the air admitted to the brake-cylinder, which may be assisted by a light spring on the release-valve, if desired, causes such release-valve to seat, and thereby close 25 the brake-cylinder exhaust to atmosphere.

The reservoir-feed controller, hereinbefore referred to, comprises an upwardly-spring-pressed valve 67, arranged to seat upon the lower portion of a bushing 68, extended upwardly to the space below the lower dia- 30 phragm 62. This bushing has a central bore 69 and radial ports 70, whereby when the feed-controller valve, which fits loosely in the lower end of the bushing, is opened the air 35 from the train-pipe is permitted to flow through passage 26, bore 69, port 70, and passages 26^a to the auxiliary reservoir. The bore 69 communicates with the space below the lower diaphragm through the ports 71, 40 so that the lower face of such diaphragm is always exposed to reservoir-pressure. The top face of the upper diaphragm 61 is always exposed to train-pipe pressure, which flows from the train-pipe connection to passages 45 27 and 27^a, the latter passage terminating in the top cap 50 and at the top face of the dia- phragm 61.

The bushing 68 makes an air-tight joint with the valve-casing, preventing the train-pipe air from passing to the auxiliary reservoir when the valve 67 is seated. When this valve is held off from its seat by the contact of the lower diaphragm with the upper end of the stem of such valve, the air feeding past 55 the piston 13 through the by-pass is free to flow by the valve 67 and to feed into the auxiliary reservoir. This is the normal condition of things with the brake-release valve open. When the influence of the said dia- 60 phragm is removed, the spring of the valve 67 will close the latter, with the result that no air can feed into the auxiliary reservoir when the brake-release valve is closed.

The operation is as follows: The train-pipe 65 air enters the valve device and into the cham-

ber 4, forcing the ports therein to the normal position in the drawings. The air feeds by the piston 13 through the by-pass or feed-groove 4^a and past valve 67, which in this condition of things is held open in the manner described. The air passes upwardly past the valve 67 and through the valve-bushing and passage 26^a to the auxiliary reservoir. The air, which is now, in effect, reservoir-air, passes through the ports to and exerts its pressure upon the under side of the lower dia- 70 phragm, which pressure is counterbalanced by the train-pipe pressure exerted upon the top face of the outer diaphragm. To set the brakes for service, a proper reduction of 75 train-pipe pressure is made, with the result that the piston 13 moves to the left, thereby closing the feed-groove, the slot-and-pin connection of the service-valve permitting the piston 13 to pass the feed-groove before such 80 valve is lifted from its seat. A further travel of the piston lifts the service-valve, thereby permitting the reservoir-air to flow past the controller-valve 67 and past the service valve to the brake-cylinder. When the pres- 85 sure in the reservoir has been reduced slightly below that in the train-pipe, the piston 13 moves to the right and seats the service-valve. When the train-pipe reduction was made, as described, the pressure on the upper dia- 90 phragm 61 was also reduced, with the result that the reservoir-pressure exerted against the lower diaphragm caused both dia- 95 phragms to be forced upwardly. The brake-cylinder release-valve is now free to be 100 closed by the first pressure entering the brake-cylinder. To release the brakes, the train-pipe pressure is increased, whereupon the piston 13 and service-valve are restored to normal position. This increased pressure 105 will also pass to the upper side of the dia- phragm, forcing both dia- 110 phragms downward, whereupon the release-valve will be unseated to exhaust or release the brake-cylinder.

The dia- 115 phragms open the release-valve before the lower one thereof abuts the stem of the valve 67 to unseat the latter, so that no train-pipe air can enter the reservoir until after the release-valve is open. The accumulating train-pipe pressure being thus un- 120 able to pass to the reservoir will keep acting against the release-valve mechanism until finally the release-valve is opened. The release-valve is thus compelled to open as the feed to the reservoir is closed until such re- 125 lease-valve is opened, with the result that the brakes are prevented from sticking and releasing of the brakes always assured.

In emergency action a considerable and sudden reduction of train-pipe pressure 125 causes the piston 13 to lift the emergency- valve, thereby first admitting the direct train pipe air to the brake-cylinder, and, owing to the particular construction of parts, subse- 130 quently admitting the reservoir-air on top of

the train-pipe pressure. The release is effected in the same manner as in service action.

I claim—

- 5 1. In a railway-brake-actuated device of the type in which a movable-abutment-actuated release-valve and a movable-abutment-actuated service-valve are independent of each other, the combination, with said 10 valves, of a feed-groove arrangement or bypass valve governed by the service-valve abutment, and a valve interposed in a passage between said service-valve abutment and the auxiliary reservoir for governing the feed to such reservoir and governed by the 15 abutment of the release-valve.
2. In a railway-brake-actuated device of the type in which a movable-abutment-actuated release-valve and a movable-abutment- 20 actuated service-valve are independent of each other, the combination, with said valves, of a feed-groove around the abutment of the service-valve, and a spring-pressed valve interposed in a passage be- 25 tween said abutment and the auxiliary reservoir for governing the feed to the latter, the abutment of the release-valve operating to press against such valve and hold it open so long as the brake-release is open.
3. The combination of a valve-casing having communication with the train-pipe, 30 brake-cylinder and auxiliary reservoir, a movable-abutment-actuated service-valve controlling the flow of fluid-pressure from the reservoir to the brake-cylinder, and operating in a chamber 4 having a feed-groove or by-pass 4^a, a valve 67 arranged in a passage 26 leading to the auxiliary reservoir, and brake-release-valve mechanism for controlling said valve.
4. In a device for actuating railway-brakes, 40 service-valve mechanism comprising a movable abutment having a stem provided with an end bore, a service-valve received in said bore, and a spring for holding such valve projected in combination with independent release-valve mechanism.
5. In a device for actuating railway-brakes, 50 service-valve mechanism comprising a movable abutment having a stem provided with a bore, a service-valve carried by such stem and having a pin-and-slot connection therewith in combination with independent release-valve mechanism.
6. In a device for actuating railway-brakes, 55 service-valve mechanism comprising a movable abutment having a stem provided with a bore, a pin received by such bore and movable therein to act as a service-valve, and a 60 spring arranged in the base or bottom of the said bore and bearing against the service-valve to normally hold it projected in com-

bination with independent release-valve mechanism.

7. In a device for actuating railway-brakes, 65 service-valve mechanism comprising a movable abutment, a service-valve carried by the abutment and having a movement independent thereof, and means independent of the service-valve for limiting the movement of 70 the abutment in the seating operation of the service-valve in combination with independent release-valve mechanism.

8. In a device for actuating railway-brakes, 75 service-valve mechanism comprising, in combination with a casing having a chamber, a movable abutment operating therein, a stop arranged in said chamber in the path of movement of the abutment, and adapted to limit the inward movement of such abutment, a 80 service-valve carried by such abutment and having a movement independent of the abutment and independent release-valve mechanism.

9. In a device for actuating railway-brakes, 85 service-valve mechanism comprising, in combination with a casing having a chamber, a movable abutment operating therein, an annular projection arranged in said chamber in the path of movement of the abutment, a service-valve carried by such abutment and having a movement independent of the abutment, and means for holding the service-valve projected with a yielding pressure in respect to the abutment and independent release-valve mechanism.

10. In a device for actuating brakes, 90 means for preventing the flow of air to the auxiliary reservoir while the brakes are set and opening a passage to such reservoir after the release-valve is open, such passage being independent of the usual by-pass or feed-groove.

11. In a device for actuating brakes, 105 the combination of release-valve mechanism, a piston governing the usual by-pass or feed-groove, and a separate valve governed by the release-valve mechanism and arranged in a feed-passage between the piston and auxiliary reservoir for opening or closing said 110 feed-passage according to the movements of the release-valve mechanism.

12. In a device for actuating railway-brakes, 115 service-valve mechanism comprising a movable abutment having a stem and a service-valve carried by and normally held projected from such stem and having a movement independent thereof in combination with independent release-valve mechanism.

R. FITZGERALD.
